(57) **CLAIM**

The ornamental design for a luggage case, as shown and described.

DESCRIPTION

FIG. 1 is a front perspective view of a luggage case showing my new design.

FIG. 2 is a front elevational view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The curved broken lines shown in FIGS. 1-3 illustrate impressed breaks in the molded front and back walls of the luggage. These breaks form part of the claimed design.
